CLAIM

The ornamental design for a grater with cover, as shown and described.

DESCRIPTION

FIG. 1 is a perspective view of a grater with cover;

FIG. 2 is a front elevation of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a perspective view of FIG. 1 shown with the cover removed;

FIG. 9 is a front elevation of FIG. 8; and,

FIG. 10 is a right side elevation view of FIG. 8.

The broken lines in the drawings depict portions of the grater with cover that form no part of the claimed design.

The oblique shade lines in FIGS. 1-7 depict a surface that is transparent.

1 Claim, 8 Drawing Sheets(56)
